UNITED STATES PATENT OFFICE.

WILLARD H. KEMPTON, OF WILKINSBURG, PENNSYLVANIA, ASSIGNOR TO WESTINGHOUSE ELECTRIC & MANUFACTURING COMPANY, A CORPORATION OF PENNSYLVANIA.

MOLD.

Application filed October 8, 1918. Serial No. 257,389.

To all whom it may concern:

Be it known that I, WILLARD H. KEMPTON, a citizen of the United States, and a resident of Wilkinsburg, in the county of Allegheny and State of Pennsylvania, have invented a new and useful Improvement in Molds, of which the following is a specification.

My invention relates to molds and more particularly to molds for use in the manufacture of bodies formed of superimposed sheets of fibrous material impregnated with a binder and it has for its primary object the provision of a mold of such character that all possibility of any pinching off of the material being molded or flow of such material between the mold sections, such as would prevent their proper closing, is prevented.

A further object of my invention is to provide a mold which is simple in construction and which may be easily assembled and disassembled to promote rapid molding.

Another object which I have in view resides in constructing a mold comprising a plurality of forming members adapted to be arranged about the article to be molded and to then be forced into the body of the mold to thereby compress the article.

In this connection, another object of my invention consists in so arranging the mold body and forming members that all of the forming members will move into the mold simultaneously although certain of the forming members will apply their pressure to the article being molded during the early part of their movement into the mold body while the remaining forming members will apply their pressure to the article during the latter part of their movement into the mold body. By this arrangement, it is possible to bring the first-mentioned forming members into engagement with the latter-mentioned forming members, before the article being molded is completely compressed, to provide a closed chamber in which the article is further compressed and from which none of the material comprising it can escape. This obviates a number of difficulties encountered in the past and insures a superior and more uniform product, as none of the material being molded can be pinched from the article and a com-

plete closing of the mold sections about the article is insured.

With these and other objects in view, my invention will be more fully described, illustrated in the drawings, in the several views of which corresponding numerals indicate like parts, and then particularly pointed out in the claims.

Fig. 1 is a horizontal sectional view taken on the line I—I of Fig. 3; Fig. 2 is a vertical sectional view taken on the line II—II of Fig. 1, showing, partially in section and partially in elevation, the article being molded; Fig. 3 is a view corresponding to Fig. 2 but taken on the line III—III of Fig. 1, that is, in a plane at right angles to that of Fig. 2.

My improved mold comprises a mold body 1, a pair of liners 2, and co-operating forming members or splits 3, a second pair of liners 4 and additional co-operating forming members or splits 5.

The mold body 1 is tubular and preferably rectangular in cross section, being open at its ends and formed centrally of two of its opposite side walls with longitudinally-extending channels 6. The channels 6 receive the liners 4 which are of substantially wedge-shape. As best shown in Fig. 3 of the drawings, the liners 4 are somewhat shorter than the height of the mold body and are formed, at their lower ends, with vertical faces 7 and above these faces with a pair of spaced upwardly and outwardly correspondingly inclined faces 8 separated by an intermediate vertical face 9.

Co-operating with the liners 4 are the forming members or splits 5 which are equal in thickness to the width of the channels 6 and the liners 4 and which have their outer edges stepped to provide wedging surfaces. The wedging surfaces, in each instance, comprise a pair of spaced, downwardly and inwardly inclined surfaces 10 and 11 separated by an intermediate vertical surface 12. The upper ends of the inclined surfaces 10 and 11 terminate slightly below the top of the forming member so that the upper portion of the forming member is vertical while its lower portion is preferably beveled, as shown at 13.

The wedge-shaped liners 2 are coextensive

with the unslotted walls of the mold body against which they are disposed and have their inner faces stepped to provide wedge surfaces. As best shown in Fig. 2, each of these liners 2 is formed, at its lower portion, with a vertical face 14, extending throughout somewhat less than half the height of the liner and above this with spaced, inclined surfaces 15 and 16 separated by an intermediate vertical surface 17. The surfaces 15 and 16 are formed at the same inclination, and the surface 16 extends to the top of the liner.

Co-operating with the liners 2 are the forming members or splits 3. Each of the forming members is provided, intermediate its length, with an inclined surface 18 and, at its lower end, with a second inclined surface 19, these two being separated by an intermediate vertical surface 20, while the forming member above the surface 15 is vertical, as shown at 21.

The liners and forming members are so proportioned that they may be positioned in the mold body in the manner clearly shown in the drawings, and the inner faces of the forming members are recessed so that, in assembled position, they provide a chamber of the size and shape of the product to be formed in the mold. In the present instance, I have illustrated a mold adapted for employment in the manufacture of strain insulators of a certain type but it will be appreciated that molds embodying the same principle may be effectively employed for molding articles of various kinds as, for instance, rods and tubes.

The strain insulator illustrated in the drawings is of the type disclosed in an application filed by me, May 13, 1918, bearing the Serial No. 222,195. The strain insulator may be formed by winding a sheet of fibrous material, such as paper, impregnated with a suitable binder as, for example, a phenolic condensation product, about a mandrel to form a green or uncured tube of any convenient length and having a wall of the desired thickness. Such a tube may then be cut to provide sections of suitable length and each section be utilized in constructing a strain insulator. When forming a strain insulator, a rod or block 22 of wood or other suitable insulating material may be inserted in one of the tube sections, and the threaded or otherwise roughened shanks of connector elements 23 may be inserted in the ends of the tube, after which the assembled article is placed in a mold and cured by subjecting it to heat and pressure to compact the material of the tube and harden its binder.

When my improved mold is employed, the liners are positioned in the mold body, the forming members are positioned about the assembled strain insulator, and the

forming members, together with the enclosed insulator, are positioned in the upper portion of the mold body. Under these circumstances, the inclined faces 18 and 19 of the forming members 3 rest upon the inclined faces 16 and 15, respectively, of the liners 2. The forming members 5 occupy similar positions, with their inclined faces 11 occupying the positions occupied by their inclined faces 10 in Fig. 2.

With the mold and the article to be molded thus assembled, pressure is simultaneously applied in any suitable manner, as by placing the mold in a heated press, to simultaneously force the forming members and the enclosed strain insulator into the mold to the position shown in the drawings.

During the first part of this movement, the inclined faces 18 and 19 of the forming members 3 ride over the inclined faces 16 and 15, respectively, of the liners 2 so that the forming members 3 compress the uncured tube of the strain insulator from opposite sides and are brought into engagement with the opposite faces of the forming members 5. In the meantime, there is no movement of the forming members 5 toward each other as the vertical faces of the forming members 5 are riding along the inner wall of the upper portion of the channels 6 and the upper vertical faces 9 of the liners 4. It is, therefore, possible for the material of the tube section to bulge somewhat toward the forming members 5 as the forming members 3 are brought toward each other and consequently, there will be no pinching off of material, as the forming members 3 come into engagement with the forming members 5 and nothing to prevent such engagement of the forming members.

During the remainder of the movement of the forming members into the mold, the vertical faces of the forming members 3 ride along the vertical faces of the liners 2 while the inclined faces 11 and 13 of the forming members 5 ride along the inclined faces 8 of the liners 4, and the forming members 3, consequently, are forced into engagement with the tube section of the strain insulator to complete its compression. After heat has been applied for a sufficient length of time, the mold may be readily disassembled by knocking the forming members, together with the enclosed insulator, from the mold body when they will immediately separate and release the insulator.

Although the mold, as illustrated, is capable of molding only strain insulators, it will be appreciated that anyone skilled in the art may suitably recess the inner faces of the forming members to adapt the mold for use in the manufacture of various articles. The liners may, obviously, be formed integrally with the mold body but in most

cases the design illustrated is preferable, as it facilitates machining the inclined faces and permits the employment of hardened liners without necessitating hardening of 5 the entire mold body.

Furthermore, somewhat different arrangements of the inclined faces may be made, without departing from the main principle of the mold which comprises the provision

10 of a mold in which certain of the forming members are brought to their final positions relative to each other and to the remaining forming members before the remaining forming members are forced into engagement with the article being molded. No 15 limitations are, therefore, to be imposed upon my invention other than those set forth in the claims.

I claim as my invention:

20 1. A mold including a body, wedge-shaped liners disposed therein and providing a chamber, and a plurality of wedge-shaped forming members adapted to surround the article to be molded and co-operating with

25 the liners to be forced toward each other as they and the surrounded article are moved into the mold, the wedge face of each liner and forming member comprising a plurality of spaced inclined surfaces.

30 2. A mold including a body, wedge-faced liners disposed therein and providing a chamber, and a plurality of wedge-faced forming members adapted to surround an article to be molded and to be forced with it 35 into the chamber, the wedge-faces of the liners and forming members being so formed relative to each other that, initially, the forming members constituting one set are forced toward each other while the forming

40 members constituting a second set have no lateral movement and, subsequently, the members constituting the first set have no lateral movement while the members constituting the second set are forced toward 45 each other.

3. A mold including a body, wedge-faced liners disposed therein to form a chamber, and a plurality of wedge-faced forming members adapted to surround an article to be molded and to be forced with it into the chamber, the wedge faces of certain opposed liners and forming members being active during the initial movement of the forming members into the chamber and, subsequently, inactive while the wedge faces of the remaining forming members are inactive during the earlier movement of the forming members into the mold and subsequently active.

60 4. A mold including a tubular body substantially rectangular in cross section, form-

ing members adapted to surround an article to be molded and to be forced with it into the body, means for causing a pair of opposed forming members to move toward 65 each other during the earlier part of their movement into the body and to maintain them in uniformly spaced relation during the latter part of the movement, and means for causing the remaining forming members 70 to maintain a uniformly spaced relation during their earlier movement into the body and to move toward each other during subsequent movement into the body.

5. A mold including a body, a plurality 75 of forming members adapted to surround an article to be molded and to be forced, with the article, into the body, means for forcing certain of the forming members into final position with respect to the article and to 80 each other and into engagement with the remaining forming members and means for subsequently forcing the remaining forming members into final position with respect to the article.

6. A mold including means providing a chamber having its opposite walls formed, each with a series of spaced downwardly and inwardly inclined surfaces, and a plurality of wedge-shaped forming members 90 adapted to surround the article to be molded and formed with a series of inclined faces for engagement with the inclined faces of the chamber, whereby the forming members will be forced toward each other, as they 95 and the surrounded article are moved into the chamber.

7. A mold including means providing a chamber having its opposite walls formed, each with a series of spaced downwardly 100 and inwardly inclined surfaces, and a plurality of wedge-shaped forming members adapted to surround the article to be molded and formed with a series of inclined faces for engagement with the inclined faces of 105 the chamber, whereby the forming members will be forced toward each other as they and the surrounded article are moved into the chamber, the series of inclined faces of the chamber walls and forming members being 110 such that a pair of forming members will be forced toward each other during a part of the movement of the forming members into the chamber while another pair of forming members will be forced toward each other during the remainder of the movement 115 of the forming members into the chamber.

In testimony whereof, I have hereunto subscribed my name this 25th day of Sept., 1918.

WILLARD H. KEMPTON.
